UNITED STATES PATENT OFFICE

HAROLD ELNO SMITH, OF CLEVELAND HEIGHTS, OHIO

ELECTRIC CONNECTION

Application filed January 10, 1924. Serial No. 685,327.

This invention relates to electric connections and has particular reference to the fittings carried by the ends of flexible conductors sometimes called "cords" and intended for attachment to lamp sockets, base receptacles, wall brackets and other screw threaded outlets. The primary objects of the invention are the provision of a cheap, simple, and reliable device which can be inserted into and withdrawn from an ordinary threaded socket by a substantially direct pull and requiring at most not more than a fractional turn to tighten and loosen. Numerous connectors are known which are attached and detached by a direct pull, but these are mostly of a specialized nature, while lamp bulbs are generally made with screw sockets. Domestic electric appliances such as cleaners, toasters, sad irons, curling tongs, heaters, portable lamps, motors, fans, etc. are generally furnished with screw plugs adapted for attachment to lamp sockets and one of the gravest inconveniences in their use is the necessary slow screwing into and out of those sockets with the accompanying twisting and kinking of the cords. Other objects of the invention are the provision of a device of this character which shall not be easily detached by pulling the cord, which shall have a minimum number of loose and movable parts, and which shall be trouble proof and non-breakable; while further objects and advantages will appear as the description proceeds.

One of the chief features of my invention is the use of a soft flexible composition such as soft rubber for holding the relatively movable parts of the device and thus dispensing with the need of small fastening parts. This soft material may comprise the entire body of the socket or only those parts and regions which require to yield or change their positions and the contact members may be either molded permanently therein or fastened mechanically thereto. Also the conductor wires or "cord" can either be molded into the composition or attached mechanically, depending upon circumstances. For the composition I prefer soft rubber cured at such time and temperature and with such small

amounts of sulphur and other ingredients as are well known in the arts for wringer rolls, cushion tires, rubber stoppers and the like, although certain oils can be vulcanized to a very satisfactory consistency for this purpose. 55

In the drawings accompanying and forming a part of this application I have shown certain physical forms in which my ideas can be embodied, although it will be understood that these drawings are intended to be merely illustrative of the general features of my invention rather than exhaustive of particular designs. Fig. 1 is a longitudinal section and Fig. 2 a transverse section of a preferred form of cord terminal embodying my improvements; Fig. 3 is a side elevation of one of the metal contact parts; Fig. 4 is a longitudinal detail view showing a modified form of end contact; Fig. 5 is a longitudinal sectional view of another desirable form of my invention; Fig. 6 is a front elevation of the same. Fig. 7 shows a slight modification of the device shown in 5 and 6; Fig. 8 is a longitudinal sectional view and Fig. 9 a cross section of another modification; Fig. 70 10 is a separated perspective view of the different metal parts thereof; Figs. 11 and 12 are illustrations of still other modified forms; and Fig. 13 is a sectional view of a typical form of lamp socket for which my improved 80 terminal is designed.

In Figs. 1 to 6 inclusive I have shown a cord terminal having a unitary body made wholly of the soft material mentioned, the flexible conductor being permanently attached thereto; and in Figs. 7 to 10 inclusive I have shown the body only as made of this material, the flexible conductor being detachably secured; while Figs. 11 and 12 illustrate yet simpler devices for the purposes in view. 85 90

First describing Figs. 1 to 4 inclusive, I have shown a body of the soft material in question having at a point intermediate its ends a rounded external knob 1 formed at the one side with a substantially cylindrical extension 2 and at the other side with the tapering extension 3. The portion 2 is formed with an axial bore 4 extending from the forward end to a point in the extension 3 beyond the knob 1 and molded in the exterior of the 100

portion 2 are a plurality of lateral contact members 5—5. In the present embodiment these contact members are three in number, and consist of springy metal arms 6 integral with a collar 7 embedded in the composition 5 of the body, the extremities of the arms being also turned inwardly as shown at 8 and their terminal portions adjacent the extremities being spirally corrugated to conform to the threads of the lamp socket. In order to increase the flexibility of the rubber body the same is longitudinally channeled out as shown at 10 in Figs. 1 and 2 between adjacent lateral members.

The flexible cord 12 may be of any customary or convenient type, and generally comprises a pair of individual insulated wires or groups of wires twisted together and surrounded by a flexible sheath. A portion of this sheath projects into the extension 3 and is 15 adhesively sealed therein. One of the individual wires or strands, as 13, is electrically connected to the ring 7, while the other, as 14, projects lengthwise through the bore 4 where it is fastened to the screw 15 carried by the member 16. This member 16 may be either of insulating or conducting material. When it is of insulating material the screw 15 at its end constitutes the terminal contact; 20 when it is of the conducting material the whole device may be considered as the end contact regardless of the position or of the existence of the screw 15. Exteriorly the member 16 is tapered as shown and the mouth 25 of the bore is preferably tapered to receive it. A rigid tube 17 which may be of either insulating or conducting material is inserted loosely in the bore 4 between the member 16 and the base of the bore.

In its ordinary state the member 16 is loose 40 in the bore as shown in Fig. 1 and the diameter defined by the contacts 5 is such as to permit them to be forced lengthwise into a standard threaded lamp socket, the flexibility 45 of the body permitting the necessary inward movement of the lateral contact members. As soon as the member 16 reaches the bottom 50 of the socket it is forced into wedging engagement with the ends of the bore thereby holding the lateral members against inward movement; the device can be seated more strongly by a small angular turn if desired. It is permissible that this wedging movement of the member 16 may be accomplished by longitudinal stretching of the extension 3, which 55 is one reason why the bore 4 is continued past the knob 1, although this depends to some extent upon the length of the tube 17 and considerable tolerance is permissible. The only 60 purpose of the tube 17 is to keep the conductor strand 14 fairly straight and it is not imperative that the same be used, although it sometimes assists in removing the device from the socket. This removal is effected 65 chiefly by an outward pull on the knob

1, which may be facilitated by a slight angular turn to the left although this is not generally necessary owing to the softness of the composition. As soon as the member 16 is freed the contact members 5 can readily approach each other by the collapsing of the bore 4, this being also assisted by the flexibility of the composition. It is very difficult to unseat the device by a lengthwise pull on the cord 12 since this serves rather to pull the member 16 into wedging relation than to remove the body from the socket. The tapered extension 3 also supports the cord and prevents any abrupt bend which might break the wires or injure the insulation..

In Fig. 4 I have shown a modified form of end contact member and connection therefor. In this embodiment the wire 14 is attached to a metal contact part 18 located at the foot of the bore 4 and having at its forward end a threaded socket receiving the shank 19 of the conical member 16^a. I have in both these embodiments shown the end contact member as removable for the purpose of introducing and withdrawing the core about which the body is molded.

In Figs. 5 and 6 a somewhat similar body is made of the same soft material, formed with a knob 1^a and a cylindrical portion 2^a having contact members 5^a separated by external grooves 10. The bore 4^a, however, opens from the rear, the forward end of the portion 2^a being closed with an integral web 20 of the rubber or other like material having embedded therein a terminal contact member 16^b. In this embodiment the different contact members 5^a are all separate from each other, being connected only by the one strand 13 of the wire, the other strand 14 being connected to the contact 16^b. I have here shown the knob 1^a as provided with a stiffening ring 21 for greater strength. The general effect of the web 20 is of a flaring or conical nature so as to permit ready yielding of the lateral contact members upon insertion into the socket, and also to wedge them outwardly upon longitudinal pressure of the contact 16^b when the same reaches the bottom of the socket. Pull on the cord 12 also tends to hold the device the more tightly, but pull on the knob 1^a tends to loosen the device. In this form the bore is also made larger for increasing the flexibility.

In both the devices heretofore described the flexible cord is permanently molded into the fitting which exhibits certain advantages in factory production, but is not applicable to retail or replacement uses. In Fig. 7 I have illustrated a modification of the device shown in Fig. 5 to fit it for retail or replacement purposes. The knob 1^a, body 2^a, bore 4^a, contact 16^b and web 20 appear as in Fig. 5. The contact members 5^b instead of being separate from each other are formed as arms from the cylindrical sleeve 24 which is lo-

cated in the bore 4^a and internally threaded for the reception of the metal sleeve 25 carried by the plug 26 which last is of insulating material and is formed with a passage-way 27 for the reception of the wire and with suitable lugs 28 whereby it may be screwed in and out. The inner end of the plug is provided with a post 29 carrying the longitudinally yielding contact sleeve 30 (a spring is here shown to permit this yielding) and the contact member 16^b terminates in a washer or other plate 31 adapted to be engaged by this sleeve. Suitable screws 32—32 are provided for the wires, which are attached to the plug 26 prior to its insertion in the body.

In Figs. 8 to 10 inclusive another type of device is shown comprising a cylindrical hollow body 2^c of the soft yielding material and a terminal or base plate 35 of some hard and rigid substance such as porcelain or hard rubber. The forward end of the member 2^c is closed as before with an inclined web 20 formed at its outer end with a projection 36 having a longitudinal bore in which the end contact member and securing screw 16^c is removably inserted. The lateral contact members 5^c consist of round headed rivets secured in the flexible parallel arms 37 of the sheet metal ring 38 inserted in the mouth of the cavity 4^c. The base plate 35 is formed with an external lip 40 loosely receiving the body 2^c and with a central aperture 41 for the flexible cord 12. Rigidly secured to the inside of this plate is a metal contact member 42 of arcuate form adapted to fit snugly within the ring 38; and this member 42 preferably subtends more than a half circle in order to make certain contact at all times notwithstanding the flexibility of the ring 38 and the softness of the body 2^c. Also carried by the member 35 is a metal bracket 43 having at its inner end a threaded hole 44 for the reception of the screw 16^c whereby the parts of the plug are held together. A hollow sleeve 45 is preferably inserted between the end of the bracket 43 and bottom of the recess 4^c. The wire terminals are secured to the member 42 and bracket 43 respectively.

Fig. 11 illustrates the simplest possible form in which a device of this character can be made, namely a plain cylindrical body 2^d of soft material having a terminal lateral contact 5^d and a terminal contact 16^d consisting merely of metal contacts to which are connected the terminals of the cord 12. This body, however, must be made of exceedingly soft material, such as spongy rubber and is not so long lived as the other devices, though it may be made more cheaply. It is sufficient if there be only a single lateral contact as shown in Fig. 11, although it is convenient to have other projections as shown at 50 even though they be dummies, to render the device sym-

metrical in appearance and also to support it centrally in the socket. Another simple form which my invention may take is shown at Fig. 12 wherein a hollow cylindrical body 2^e of soft material has a conical forward end 20^e and a metal ring 51 surrounding its open end and preferably molded in place. The lateral contacts consist of brass screws 5^e clamped upon one strand of the cord 12 while the terminal contact consists of another brass screw 16^e clamped upon the other strand of the cord. A knob part 52 is detachably secured by means of screws 53 in the ring 51.

In order that there may be no misunderstanding relative to what I mean by "socket" I have illustrated in Fig. 13 a simple illustration of a typical form for which my improvements are designed, the same comprising a shell 55 formed with rounded helical corrugations and located inside an insulating body 56. At its bottom the socket is closed by a base part 57 carrying a central contact member 58 insulated from the shell 55. The socket wires are fastened to suitable screws 59, 59.

When my improved plug is made separable as shown in Figs. 7 to 10 inclusive the parts thereof are preferably attached to the end contact rather than the side contacts in order that the lateral movement of the latter may not be impeded. Indeed by making the device in the form of a more or less stiff central core surrounded by a soft flexible sleeve on which the side contacts are carried, the insertion of the core facilitates the entering of the side contacts by the longitudinal stretching thereof, while the withdrawal of the core tends to shorten and thicken the sleeve, thereby holding it the more tightly. Similarly if the plug be turned clockwise when fully inserted the same bunching will occur, but this can be stopped at any desired limit by adjusting the hardness of the composition changing the size of the central cavity, or the width and depth of the external notches. The lateral contacts may vary in length and number from a single stud located at one side to several longitudinal serrated strips. I prefer to employ three contacts equidistantly spaced about the periphery since these serve to center the plug and insure good electrical connection. It will be apparent, however, that many and great changes may be made in design and appearance and I do not restrict myself except as shown in the prior art.

Having thus described my invention what I claim is:

1. An electric cord terminal for threaded sockets comprising a body of soft flexible insulating material such as soft rubber having a contact member at its end adapted to engage the bottom of the socket and one or more circumferentially spaced, longitudi-

- nally projecting contact members of limited angular extent in its side wall adapted to engage the side wall of the socket, the interior of said body having a hollow bore, and 5 the lateral contact members having projections adapted to be held yieldingly by said flexible body in engagement with the threads of the socket to which the terminal is applied.
- 10 2. An electric cord terminal for threaded sockets comprising a body of soft flexible insulating material such as soft rubber, the end of said body having a projection, a contact member carried by said projection adapted to engage the bottom of the socket and one or more circumferentially spaced, longitudinally projecting contact members of limited angular extent carried by the side of said body near its end adapted to engage the 15 side wall of the socket, the exterior of said body being longitudinally channeled between adjacent contact members.
- 20 3. An electric cord terminal for threaded sockets comprising a hollow body of soft flexible insulating material such as soft rubber having a contact member at its end adapted to engage the bottom of the socket and one or more longitudinally projecting contact members of limited angular extent in the side 25 wall adapted to engage the side wall of the socket, and the lateral contact members having projections adapted to be held yieldingly in the threads of the socket to which the terminal is applied.
- 30 4. An electric cord terminal adapted to be inserted into and withdrawn from a threaded socket by a direct pull, characterized by having longitudinally extending radially yielding contact members molded in and carried 35 by a soft flexible substance such as soft rubber, said contact members having projections adapted to be held yieldingly by said substance in the threads of the socket to which the terminal is applied.
- 40 5. An electric cord terminal adapted to be inserted into and withdrawn from a threaded socket by a direct pull, characterized by having a central substantially rigid core and a sleeve of soft flexible material as soft rubber 45 surrounding said core, and one or more lateral contacts carried by said sleeve, said contacts having portions molded in and submerged by said flexible material and also having projections adapted to be held yieldingly by the 50 elasticity of said sleeve in contact with the threads of the socket to which the terminal is applied.
- 55 6. An electric cord terminal adapted to be inserted into and withdrawn from a threaded 60 socket by a direct pull, characterized by having a central substantially rigid core and a sleeve of soft flexible material as soft rubber surrounding said core, the end of said core engaging said sleeve, and one or more lateral 65 contacts carried by said sleeve, said contact members having projections adapted to be held yieldingly by said substance in the threads of the socket to which the terminal is applied.
7. An electric cord terminal adapted to be inserted into and withdrawn from a threaded socket by a direct pull, characterized by having a central substantially rigid core and a sleeve of soft flexible material as soft rubber surrounding said core, the forward end of 70 said core having a terminal contact and said core also engaging said sleeve, and one or more lateral contacts carried by said sleeve, said contact members having projections adapted to be held yieldingly by said substance in the threads of the socket to which the terminal is applied.
- 75 8. An electric cord terminal comprising an elongated body of soft flexible material as soft rubber, having in its exterior surface a plurality of longitudinal grooves, and ribs between said grooves, lateral contact members carried by said ribs, and an end contact member carried by said body.
- 80 9. An electric cord terminal comprising an elongated body of insulating material having spaced longitudinal portions of soft flexible material such as soft rubber, and laterally facing contact members carried by said flexible portions and adapted to yield transversely so as to be insertible into or withdrawable from a threaded socket by a direct pull.
